UNITED STATES PATENT OFFICE.

PASQUALE SANTA EMMA, OF VENICE, CALIFORNIA.

CORNET-MUTE.

1,342,846.

Specification of Letters Patent.

Patented June 8, 1920.

Application filed April 29, 1919. Serial No. 293,416.

To all whom it may concern:

Be it known that I, PASQUALE SANTA EMMA, a citizen of the United States of America, residing at the city of Venice, county of Los Angeles, State of California, have invented a new and useful Improvement in Cornet-Mutes, of which the following is a full, clear, concise, and exact description, reference being had to the accompanying drawings, which form a part of this specification.

My invention relates generally to mutes, and more particularly to mutes especially adapted and designed for use in connection with cornets and other musical instruments of the horn variety.

One object of my invention is to provide a mute comprised of double annular walls which join at one end, forming a central passage, flared at one end, and an annular chamber with a closure at one end, surrounding the central passage.

In the accompanying drawings Figure 1 is a side elevation of the mute.

Fig. 2 is a vertical sectional view of the mute inserted in the outlet of a cornet.

Fig. 3 is an end elevation of the front end of the mute.

Fig. 4 is an end elevation of the opposite end of the mute.

Referring to the drawings there is provided a bell 1, comprising an inner wall 2, and an outer wall 3, providing a central passage 4, and an annular chamber 5 surround-

ing the central passage. The walls 2 and 3 are flared at one end providing an enlarged outlet 6 for the central passage 4. The walls 2 and 3 are joined adjacent the outlet 6 forming a closure for the annular chamber 5.

The annular chamber 5 has an intake 7 adjacent the intake 8 of the annular wall 2.

The exterior of the mute is of a general shape adapted for insertion within the outlet of a cornet or other musical instrument 45 of the horn variety. If needed, tape or other suitable material is put around the neck of the mute to secure a tight fit within the horn.

What I claim as my invention is:— 50

A mute for a cornet or other musical instruments of the horn variety, comprising double annular walls, providing a round central passage and an annular chamber surrounding the central passage, the central 55 passage being flared at one end, and the annular wall of the central passage and the annular wall of the annular chamber being joined adjacent the outlet of the central passage forming a closure for the annular 60 chamber.

In witness whereof I have hereunto set my hand at Los Angeles, California, this 19th day of April, 1919.

PASQUALE SANTA EMMA.

Signed in the presence of—

WILLIAM B. GILROY,
WALTER J. LITTLE.
